BENJAMIN F. HOWARD, OF INDIANAPOLIS, INDIANA, ASSIGNOR OF ONE-HALF TO
JOHN W. STAUB, OF INDIANAPOLIS, INDIANA.

LUBRICATOR.

1,086,052.

Specification of Letters Patent.

Patented Feb. 3, 1914.

Application filed January 10, 1913. Serial No. 741,188.

To all whom it may concern:

Be it known that I, BENJAMIN F. HOWARD, a citizen of the United States, residing at Indianapolis, in the county of Marion and 5 State of Indiana, have invented certain new and useful Improvements in Lubricators, of which the following is a specification.

The object of this invention is to provide an efficient and inexpensive device for lubricating the cylinders and pistons of steam pumps and other minor power generators, and to that end the object is to nebulize the lubricant oil and thoroughly mix it with steam, and then discharge the mixture into 15 the pipe which supplies steam to the cylinder of the motor.

I accomplish the objects of the invention by the mechanism illustrated in the accompanying drawing, wherein the invention 20 is illustrated in elevation and partial vertical section.

Referring to the drawing, 1 is the main steam supply pipe through which live steam is conveyed in the direction of the arrows, 25 to the cylinder of a steam motor (not shown).

2 is an oil container into the upper end of which the pipe 3, from a steam condenser 4, is introduced and extends to near the bottom of the oil container 2. The condenser 4 is connected by a branch pipe 5 with the main steam supply pipe 1, and the pipe 5 has a valve 6 by which the discharge through it is regulated. The container 2 has a glass 35 gage 7, on one side through which the height of oil in the container is shown, and on the diametrically opposite side of the container is a stand pipe 8 communicating at its lower end with the container 2, near the bottom 40 of the latter. The stand pipe 8 discharges at its upper end, which is near the top of the container 2, into a horizontal pipe 9. The stand pipe will preferably comprise a glass section through which the globules of 45 oil rising therein may be discerned. The pipe 8 is filled with water, glycerin or the like, in which the oil globules are floated to the level of the pipe 9 through which they are discharged. Between the pipe 3, and 50 the discharge to the stand pipe 8 is a division wall 10 in the oil container making a closure at the bottom of the latter but open at its upper end for the passage of the lubricant over it.

All of the parts thus far described are of 55 the usual and well known construction.

The lubricant delivered by the above described mechanism into the horizontal pipe 9, has heretofore usually discharged directly into the steam pipe 1 without nebulization 60 or further mixture with steam, and it is between the stand pipe 8 and pipe 1, in the pipe 9 that my invention is employed to nebulize and thoroughly mix the oil vapors with steam before discharge into the pipe 1. 65 To this end I provide a mixing chamber 12, into which the pipe 9 discharges through a downwardly sloping reduced nozzle or spout 13, and in front of the discharge end of the nozzle 13, I provide a nozzle 14 which 70 discharges a jet of steam under pressure in a downward vertical direction across the end of nozzle 13, and forms an atomizer in connection with the nozzle 13, which, when the two nozzles are properly adjusted in 75 keeping with the steam pressure through nozzle 14, thoroughly nebulizes the oil as it is delivered through the nozzle 13, and discharges it forcibly against the oblique lower wall of the mixing chamber 12. The 80 lower end of the mixing chamber 12 is the discharge end of the latter, and it is provided with a series of oppositely disposed interlapping baffle plates 15 and 16 which aid to additionally break up the oil globules 85 and mix the reduced particles with the steam. The last baffle plate will preferably be sloped in a direction to discharge the mixture in the general direction of the steam flow in the pipe 1.

Steam is supplied under pressure to the nozzle 14, from the pipe 5, through the pipe 18, and the pipe 18 will preferably be provided with a valve 19 for regulating the discharge through it. The nozzle 14 is 95 threaded throughout its upper outer portion and screws into a sleeve 20, which is the continuation of the pipe 18 but is jointed at 21 with the latter to permit separation, and access to the nozzle in sleeve 20. 100 The upper inner end of the nozzle 14 has its walls flattened to engage a wrench which is inserted by disconnecting the pipes 18 and 20 at joint 21 to permit of such access, and by means of the wrench the nozzle 14 may 105 be screwed up or down in the sleeve 20 to adjust the distance of the end of nozzle 14 from the end of the spout or nozzle 13.

It will be observed that my invention is constructed in such a manner that it is readily applicable to use with lubricators now in common use, to render the latter 5 more economical in the use of lubricants, and more efficient.

While I have described my invention with more or less minuteness as regards details of construction and arrangement and as being embodied in certain precise forms I do not desire to be limited thereto unduly or any more than is pointed out in the claims. On the contrary, I contemplate all proper changes in form, construction and arrangement, the omission of immaterial elements 15 and the substitution of equivalents as circumstances may suggest or necessity render expedient.

I claim:

20 1. The combination with a main steam pipe, of a mixing chamber discharging in a downwardly oblique direction into said pipe, a nozzle discharging oil into said chamber, a second nozzle discharging steam under

pressure across the discharge end of the oil 25 discharging nozzle and against an oblique wall of said chamber, and baffle plates in the chamber between its discharge end and the said nozzles.

2. The combination with a main steam 30 pipe, of a mixing chamber discharging in a downwardly oblique direction into said pipe, a nozzle discharging oil into said chamber, a second nozzle discharging steam under pressure across the discharge end of 35 the oil discharging nozzle and against an oblique wall of said chamber, baffle plates in the chamber between its discharge end and said nozzles, and means for adjusting the relative positions of the two nozzles. 40

In witness whereof, I, have hereunto set my hand and seal at Indianapolis, Indiana, this, 21st day of December, A. D. one thousand and nine hundred and twelve.

BENJAMIN F. HOWARD. [L. S.]
